Attorney

UNITED STATES PATENT OFFICE.

MAX YABLICK, OF NEWARK, NEW JERSEY, ASSIGNOR TO MINE SAFETY APPLIANCE COMPANY, OF PITTSBURGH, PENNSYLVANIA, A CORPORATION OF PENNSYLVANIA.

FLUTTER VALVE.

Application filed November 3, 1924. Serial No. 747,437.

This application is a continuation-in-part of my application Ser. No. 552,529 filed Apr. 14, 1922.

This invention relates to one-way valves of flexible material and more specifically to improvements upon the type of valves commonly known as "flutter" valves which are extensively employed in gas masks for the discharge of exhaled air therefrom, although not necessarily limited to such use.

It is customary to provide means in connection with respirators or gas masks to readily permit outflow of the exhaled air. This means should positively and effectively close during inhalation to prevent admission of air therethrough, so that the air which is breathed in is taken entirely from the fresh air compartment or through the air purifying means as the case may be.

The "flutter" valve heretofore employed for this purpose consisted of a bag of soft, pliable rubber, connected at one end with a fitting through which the air is exhaled, and provided with slits at the other end. The walls of the bag were arranged to lie directly one upon the other, and in exhaling, the walls separated sufficiently to permit the air to pass therethrough and out through the slits. In inhaling, the natural arrangement of the walls together with the suction caused by inhaling pulled the walls of the tube or bag tightly together and prevented entrance of air therethrough.

One of the disadvantages of this type of valve is that it does not afford absolute safety against the entrance of atmospheric air therethrough into the mask when the wearer inhales. Thus, if solid particles, such as sand, grit, etc., become lodged between the walls of the bag, the valve will not close tightly and therefore fail to function properly. The necessary protection is thus lost.

Another disadvantage of this type of valve is that when placed upon the fitting of the mask through which the exhaled air passes, the valve projects a considerable distance beyond the face-piece of the mask, thus greatly interfering with the freedom of movement of the wearer. This disadvantage is further accentuated by the fact that these valves of pliable rubber are almost invariably protected by a surrounding frame of rigid material, such as metal, and this rigid frame also projects beyond the face-

piece of the mask at even a greater distance than the valve itself.

In my co-pending application Ser. No. 552,529, I have disclosed an improved valve which overcomes these disadvantages and when this valve is placed upon a gas mask or respirator renders it more compact and more efficient.

The present invention consists in a combination of the valve disclosed in my co-pending application with a sound-intensifying construction, preferably embodied in one of the walls of the flutter valve. The object of having this sound-intensifying portion is to render audible the words or sounds produced within the mask by the wearer and thus add to the efficiency and comfort of the mask.

Other, further and more specific objects of the invention will become readily apparent to persons skilled in the art from a consideration of the following description taken in conjunction with the drawings, wherein:

Fig. 1 is a perspective view of a preferred form of my device.

Fig. 2 is a section through the center of the valve, showing the position of the walls of the valve when in closed position.

Fig. 3 is a section similar to Fig. 2, showing the position of the walls when air is being exhaled through the valve.

Fig. 4 is a modification showing specific means for adding rigidity to the neck.

Fig. 5 is a modification illustrating the use of a perforated diaphragm at the base of the neck of my device.

My preferred device comprises the bag-shaped construction of the ordinary flutter valve having the walls 1 and 2 of flexible or pliable material, which is usually molded rubber. The walls are joined at their edges, except at the openings 3 and 4. To one of these walls is attached a neck 5 at a right angle or other angular relationship, preferably integral therewith and of the same material, and this neck is adapted to be placed over the fitting of the mask through which air is exhaled. The walls 1 and 2 are also preferably integral at the edges 6, 7 and 8, the smaller edges 9 being cemented at 10.

When exhaled air from the mask enters the valve through the neck 5, the walls 1 and 2 will separate as shown in Fig. 3, 110.

and the air will pass out through the openings or slits 3 and 4. On inhalation, suction occurs at the neck 5 of the valve and the walls 1 and 2 will close together as shown 5 in Fig. 2. The base 11 of the neck 5 forms a seat against which the wall 2 is drawn, thus closing the valve against incoming air. Ordinarily, when the wearer of a mask equipped with this valve inhales, the base 10 11 and wall 2 constitute the valve-closing mechanism, but if for any reason these parts should fail to function properly or perfectly, an additional protection is provided by the extended walls 1 and 2, since any suction at 15 the base will cause the walls 1 and 2 to come together at the slits as in the ordinary flutter valve. It is, therefore, clear that my device provides additional protection to that afforded by the ordinary flutter valve.

20 When the wearer of an ordinary gas mask talks, the sound of the voice is considerably decreased, and is in most cases practically inaudible. In order to amplify this sound, I have provided my flutter valve with 25 a sound-intensifying portion 12, which is preferably disposed adjacent to the base 11 of the neck 5. This sound-intensifying portion may consist of a disc secured to the wall 2 of the valve by an adhesive or other 30 suitable binding means, or else this portion of the wall may be hardened, as shown in Figs. 2 and 3. The sounds produced within the mask will cause the hardened portion 12 or sound-intensifying disc to vibrate and thereby amplify the sounds to a material 35 extent and render audible sounds which otherwise could not be readily heard.

In the construction shown in Figs. 2, 3 and 4, the base 11 of the valve is thickened so 40 as to add rigidity to the neck of the valve. In the construction shown in Fig. 4, added rigidity is produced by means of an inner tube 13 of metal which may be the fitting 45 of the mask over which the neck of the valve is placed. This tube 13 may extend below the wall 1 so as to engage with the bottom wall 2 or the disc 12 attached thereto to form the valve-closing mechanism. In 50 the illustration the tube 13 does not extend so as to engage the wall 2 or vibrating member 12 which engages the base 11 of the neck to form the auxiliary valve-closing mechanism.

In the construction shown in Fig. 5, a perforated disc 14 of metal, hard rubber or other suitable material is attached to the wall so as to embrace the opening from the neck 5 of the valve to the portion between the walls 1 and 2. This serves as a means for 55 preventing indentation of the wall 2 or more specifically the sound-amplifying portion 12 of the wall 2 when suction is taking place in the valve.

Using my device, the neck 5 is placed over 60 the fitting of the mask through which the

exhaled air passes. The walls 1 and 2 of the valve will assume a position substantially parallel to the face-piece of the mask instead of projecting outwardly therefrom as do the ordinary flutter valves, thus doing 70 away with the interference of movement of the wearer of the mask. Also, if a rigid protecting frame is used with my valve it will be substantially parallel to the face-piece of the mask. 75

If solid particles become lodged between the walls of the ordinary flutter valve, it would fail to give the necessary security, but with my valve the additional valve-closing mechanism would afford the proper protection against inhaling air therethrough. 80 Also, the additional sound-amplifying means enables the wearer to speak so as to be readily heard and understood.

The present invention is not limited to the specific details set forth in the foregoing examples which should be construed as illustrative and not by way of limitation, and in view of the numerous modifications which may be effected therein without departing from the spirit and scope of this invention, it is desired that only such limitations be imposed as are indicated in the appended claims. 85 90 95

I claim as my invention:

1. A flutter valve comprising a pair of walls, one of said walls including a vibrating, sound-intensifying portion and the other wall being provided with a neck at an angle thereto and the base of said neck being adapted to engage with the first-named wall to form a valve-closing mechanism and means at the base of said neck for guarding the wall having the sound-intensifying portion against excessive inward indentation by 105 suction. 100

2. In a flutter valve, a flattened bag of pliable rubber slitted along the edge near an end thereof and forming a valve-closing mechanism, one wall of said bag including a vibrating, sound-intensifying portion and the other wall being provided with a neck at an angle thereto and the base of said neck being adapted to engage with the first-named wall to form an auxiliary valve-closing mechanism and means at the base of 110 115 said neck for guarding the wall having the sound-intensifying portion against excessive inward indentation by suction.

3. A flutter valve of flexible material comprising a pair of walls, one of said walls including a vibrating, sound-intensifying portion and the other wall being provided with a neck at an angle thereto and the base of said neck being adapted to engage with the first-named wall to form a valve-closing mechanism and a perforated dia- 120 125 phragm at the base of said neck.

4. In a flutter valve, a flattened bag of pliable rubber slitted along the edge near 130

- an end thereof and forming a valve-closing mechanism, one wall of said bag including a vibrating, sound-intensifying portion and the other wall being provided with a neck 5 integral therewith and at an angle thereto and the base of said neck being adapted to engage with the first-named wall to form an auxiliary valve-closing mechanism and a metallic perforated diaphragm at the base 10 of said neck.
5. In a flutter valve, a flattened bag of pliable rubber slitted along the edge near an end thereof and forming a valve-closing mechanism, one wall of said bag including 15 a vibrating, sound-intensifying portion and the other wall being provided with a neck at an angle thereto and the base of said neck being adapted to engage with the first-named wall to form an auxiliary valve-clos- 20 ing mechanism and means at the base of
- said neck for guarding the wall having the sound-intensifying portion against excessive inward indentation by suction and means for adding rigidity to said neck.
6. In a flutter valve, a flattened bag of 25 pliable rubber slitted along the edges near an end thereof and forming a valve-closing mechanism, one wall of said bag including a vibrating, sound-intensifying portion and the other wall being provided with a neck 30 integral therewith and at an angle thereto and the base of said neck being adapted to engage with said disc to form an auxiliary valve-closing mechanism, a metallic perforated diaphragm at the base of said neck 35 and stiffening means at the base of said neck for adding rigidity thereto.

In testimony whereof I affix my signature.

MAX YABLICK.
